TROUSERS AND SKIRT HANGER

Laurence W. Van Dusen, Escondido, Calif., assignor to
Mission Industries, Escondido, Calif., a corporation of
California

Filed Nov. 14, 1960, Ser. No. 69,225
15 Claims. (Cl. 223—96)

This invention relates to garment hangers and has
particular reference to a new and improved hanger for
trousers and skirts.

This application is a continuation-in-part of my co-
pending application, Serial No. 703,599, filed December
18, 1957, now abandoned.

At the present time it is customary to hang trousers
either by folding them transversely over the lower bar
of a conventional coat hanger, or by suspending them
upside down from the cuffs in any of several types of
hangers specifically designed for this purpose. None
of these methods and/or devices are entirely satisfac-
tory, however. Folding the trousers will often cause
the creases to be removed or other undesirable creases
to be formed. The cuff-type hangers are extremely diffi-
cult to use in that great dexterity is required to install
and remove the trousers on or from the hangers. One
of the principal objects of this invention is, therefore,
to provide a novel garment hanger which is not subject
to the above and other disadvantages of those used here-
tofore.

Another object of this invention is to provide a cuff-
type trousers hanger which is extremely easy to use in
attaching trousers or skirts to or removing them from
the hanger.

Another object of the present invention is to pro-
vide a trousers hanger which is adapted to support a
pair of trousers in any one of several ways, i.e., in the
inverted position, either directly from the cuffs or from
a point immediately above the cuffs; in the upright position,
i.e., hanging from the waist; or in the more con-
ventional folded position.

Still another object of the present invention is to pro-
vide a novel trousers and skirt hanger which is highly
effective in use, yet which is adapted to be manufactured
economically on a quantity basis.

Other objects and advantages of the present invention,
it is believed, will be readily apparent from the follow-
ing detailed description of a preferred embodiment there-
of when read in connection with the accompanying draw-
ings.

In the drawings:

FIGURE 1 is a side elevation of the device of the
present invention.

FIGURE 2 is a rear elevation thereof.

FIGURE 3 is a top plan view, partly in section.

FIGURE 4 is a top plan view, partly in section, illus-
trating the gripping legs in the open position.

FIGURE 5 is a sectional view taken substantially on
the line 5—5 of FIGURE 1.

FIGURE 6 is a sectional view taken substantially on
the line 6—6 of FIGURE 1.

FIGURE 7 is a side elevation of a modified form of
the invention.

FIGURE 8 is a top plan view thereof partly in hori-
zontal section.

FIGURE 9 is a fragmentary, partial sectional view
similar to FIGURE 8, but illustrating the gripping legs
in the open position.

FIGURE 10 is a sectional view taken substantially
on the line 10—10 of FIGURE 7.

FIGURE 11 is a sectional view taken substantially on
the line 11—11 of FIGURE 7.

2

FIGURE 12 is a sectional view taken substantially
on the line 12—12 of FIGURE 7.

Referring now to the drawings, the hanger illustrated
therein includes a pair of elongated gripping members
or legs 10 and 11 each provided with a central bore 12,
13 extending from one end and terminating short of the
other end of each leg. The legs 10 and 11, preferably
of wood or plastic material, are generally cylindrical
in shape, but are provided with central reduced portions
14 and 15 respectively so that in the normal, closed
position the central portions of the legs are spaced apart
to provide clearance for the trousers or skirt seams.

The legs 10 and 11 are each rotatably carried on
one of a pair of straight portions 20 and 21 of a single
length of relatively heavy steel wire generally indicated
22. The portions 20 and 21 extend into the respective
bores 12 and 13, disassembly of the legs from the wire
portions being prevented by means of a pair of pins
25 and 26, one inserted partly through each of the legs
into one of a pair of annular grooves 28 and 29 formed
in each of the portions 20 and 21 adjacent the ends
thereof.

The wire portions 20 and 21 extend through a re-
tainer block 30 which is provided with a bore 31 for
the portion 21 and a transverse groove or slot 32 for
the portion 20. The portion 20 is secured to the block
by means of a pin 33. These portions 20 and 21 then
merge into upstanding, outwardly divergent wire por-
tions 35 and 36, respectively, which latter portions merge
into the angularly inclined, convergent portions 38 and
39 at the curved portions 40 and 41. The hook member
45 is formed of a U-shaped portion of the wire 22, the
two legs of the hook member merging into the respective
portions 38 and 39.

In use of the hanger, it is held in one hand with the
trousers or skirt in the other. The portions 35 and 36,
and 38 and 39, are squeezed together, by grasping these
portions in one hand, most conveniently with one of the
curved portions 40 and 41 placed centrally of the palm
40 of the hand of the user. This squeezing action forces or
spreads the portions 20 and 21 and their associated legs
10 and 11 apart as shown in FIGURE 4, the block 30 act-
ing as a fulcrum in the embodiment shown, whereupon
the trousers or skirt are then easily placed therebetween
in the desired position for hanging. Upon release of
the squeezing pressure, the garment is securely gripped
and supported by the legs 10 and 11 due to the resiliency
of the wire 22. A preferred method for hanging trousers
is illustrated by the phantom lines of FIGURE 1, wherein
50 the trousers are gripped just above the cuffs. After in-
stallation of the garment, the hanger and garment as-
sembly is simply hooked on a closet pole from the hook
45 in the customary manner.

From the above description it will be understood that
55 the hanger is extremely easy to use, particularly inasmuch as the portions 35, 36, 38 and 39 form a natural
handle for the hand of the user, which handle is also the
operating means for opening and closing of the legs 10
and 11.

60 The hanger of the present invention is sufficiently
flexible in manner of use that it can support trousers in
several ways, as well as supporting a skirt or skirts.
Trousers may be supported as shown or directly from the
cuffs, as well as by merely inserting the knee portion of
65 the trousers between the leg members 10 and 11 and then
folding the trouser legs over one or the other of the leg
members 10 and 11. Moreover, the trousers may be
supported in the upright position by doubling them over
70 at the waist and then inserting the doubled-over portion
between the leg members 10 and 11. Skirts are hung
in the same manner, i.e., by folding or doubling over the

waist portion. Two or more skirts or pairs of trousers may be supported on a single hanger if desired.

It will be observed that in the normal opening operation illustrated in FIGURE 4, the legs 10 and 11 are spread apart primarily by a pivoting or hinging action of the portion 21 with respect to the block 30. It should be pointed out, however, that this action is supplemented by an outward bodily movement of the end of the portion 20 within the block in the case of relatively thick garments, the portion 20 being free to move in the slot 32.

A modified form of the invention is illustrated in FIGURES 7-11 and is generally similar to that described above, including a clamping portion comprising a pair of garment supporting members or legs 10a and 11a. In the form shown, the legs are molded of plastic and are virtually identical with the exception of the interlock structure described below. The legs are each provided with relatively flat opposed garment-contacting faces having mating serrated surfaces 50 and 51. Each leg also has a reinforcing rib 52, 53, the legs being slightly outwardly bowed to space apart the central portions thereof (see FIGURES 8 and 9), providing clearance for the trousers or skirt seams.

A handle portion 55 is provided, formed by a pair of extensions 56 and 57 integral with the respective legs 10a and 11a. The extension 56 is provided with a ribbed side surface 58 and a pair of spaced, central webs 59. The extension 57 is also provided with a ribbed side surface 60, and has a single control web 61 which fits into the space between the webs 59 in a tongue and groove or interlock type of relationship.

Fulcrum means are provided adjacent one end of the clamping portion and as shown in the drawings, these means may include a transverse bead or rib 65 on the leg 11a and a mating slot 66 on the leg 10a, the rib and slot interlocking to provide a fulcrum for movement of the legs to the open position shown in FIGURE 9.

Spring means are provided to act upon the clamping portion about said fulcrum and as shown in the drawings, these means may include a single length of relatively heavy steel wire generally indicated 22a terminating in a pair of straight portions 20a and 21a. The portions 20a and 21a merge into upstanding, inwardly converging wire portions 35a and 36a, respectively, which latter portions merge into angularly inclined, converging portions 38a and 39a. The hook member 45a is formed of a U-shaped portion of the wire 22a, the two legs of the hook member merging into the respective portions 38a and 39a. The portion 20a and the lower part of the portion 35a are received in a slot 70 formed in the leg 10a by means of a pair of spaced flange portions 71 and 72 and by an inclined plane or wall portion 73. The flange 71 terminates at 74, leaving an opening between the point 74 and the end of the slot 70 which is formed by a front wall portion 75 of the extension 56. A flange 76 extends outwardly from the wall portion 75 and terminates in an inwardly-turned shoulder 78 behind which is positioned the portion 35a. An identical slot 70a is provided in the leg 11a for the reception of the portion 21a and the lower part of the portion 36a.

Prior to assembly, the portions 20a, 35a, 38a and the portions 21a, 36a, 39a, each lie in one of a pair of parallel planes. That is, the portion 20a is parallel to the portion 21a, the portion 35a is parallel to the portion 36a, and the portion 38a is parallel to the portion 39a. In assembly of the device, the two plastic legs and associated extensions are placed together in the position shown in FIGURE 8, and the end portions 20a and 21a are spaced apart (causing them to assume a slight "toed-in" aspect with the free ends somewhat closer together than the points of connection with the respective portions 35a and 36a) to permit them to straddle the legs. The end portions are then slipped into the slots 70 and 70a and the portions 35a and 36a are inserted into the respective openings between the flanges 71 and the shoulders 78,

whereupon the portions 35a and 36a are squeezed together to clear the shoulders 78 and the wire 22a is moved bodily toward the handle portion until the portions 35a and 36a meet the wall portions 75. The portions 35a and 36a are then released and they spring out to the first assembled position shown in the drawings. Preferably, although not essentially, the inclined plane portions 73 are provided with small protuberances 80 against which the ends 81 and 82 of the wire 22a seat.

In the assembled position the wire 22a is under tension and acts as a spring to continuously urge the legs into generally parallel clamping relationship. Thus, the ends 81 and 82 exert opposing inward forces upon the inclined planes 73 at points on one side of the fulcrum, and the portions 35a and 36a exert opposing outward forces upon the flanges 76 on the other, or handle side of the fulcrum. It should be pointed out, however, that the contact points of the portions 35a and 36a need not be on the handle side of the fulcrum, but can be on the same side as the contact points of the ends 81 and 82 if desired.

The hanger of FIGURES 7-12 is used in essentially the same manner as that of FIGURES 1-6, except that here the hanger is opened for insertion of the trousers or skirt by the application of squeezing force upon the handle or extension 56 and 57. Here again, it will be understood that in use, the legs are free to move apart in general parallel relationship so that once the garment is clamped between the legs, the bead 78 separates from the groove 79, and the tension of the wire member is transmitted evenly through the points of contact between the wire and the legs so that the clamping force of the legs is applied over the entire lengths thereof.

In addition to possessing the advantages described above, the hanger of FIGURES 7-12 is of enhanced construction in that it comprises only three parts which are quickly and easily assembled without the use of tools or the necessity for skilled workmanship. The leg members are maintained in the proper parallel relationship by means of the wire 22a, assisted by the interlock structures of the fulcrum and the extensions. The hanger structure is simple yet highly effective and it is extremely compact in size, particularly in the lateral dimension so that it takes up little room in the closet.

Having fully described my invention, it is to be understood that I do not wish to be limited to the details set forth, but my invention is of the full scope of the appended claims.

I claim:

1. A clamp type garment hanger for pants, skirts and the like having a horizontally extending clamping portion, a handle portion, a hook portion, fulcrum means adjacent one end of the clamping portion and spring means acting on said clamping portion about said fulcrum means; said clamping portion comprising a pair of horizontally elongated garment-supporting members having longitudinally extending opposed faces normally in contact for at least a portion of their length; said handle portion including spaced elements connected to said members and having portions extending beyond the fulcrum point adjacent the fulcrum end, said members extending in cantilever fashion from one end of the handle portion and being connected together by said spring means at the handle end, said spring means continuously urging said members about said fulcrum means into generally parallel clamping relationship, and said members being movable with respect to each other at the fulcrum point to maintain general parallelism of said members when a garment is supported thereon; said hook portion extending from the handle portion end and forming a point of support above the approximate horizontal midpoint of said clamping portion, the spaced elements of said handle portion providing a squeezing means adapted to be grasped by the hand to open the garment-supporting members about said fulcrum means.

2. A garment hanger as defined in claim 1 wherein said handle portion, hook portion and spring means comprise a single length of bent wire.

3. A garment hanger as defined in claim 1 wherein said fulcrum means comprises a block having a bore and a transverse slot therethrough, and said handle portion, hook portion and spring means comprise a single length of bent wire having a pair of end portions, one end portion of said wire extending through said block bore and connected to one of said garment-supporting members and the other end portion of said wire extending through said transverse slot and connected to the other of said garment-supporting members, said wire diverging from said end portions beyond the fulcrum block to form the spaced elements of said handle portion and then converging and bending to form said hook portion.

4. The structure as defined in claim 3 wherein the end portions of said wire are inserted in longitudinal bores in the fulcrum ends of the respective garment-supporting members.

5. The structure as defined in claim 3 wherein said wire is bent upwardly and outwardly from the end portions to the rear of said fulcrum block to form the diverging portion, is bent inwardly over the fulcrum end of the garment-supporting members to form the converging portion and then terminates in a substantially U-shape at the hook portion.

6. The structure as defined in claim 1 wherein the garment-supporting members are plastic and are each provided with walls forming a slot extending into the sides thereof, wherein said hook portion and spring means comprise a single length of bent wire, and wherein the end portions of said wire are received in said slots.

7. The structure as defined in claim 6 wherein the handle portion comprises a pair of extensions of said garment supporting members.

8. The structure as defined in claim 7 wherein the fulcrum means comprises a pair of cooperating members, one on each of said garment-supporting members.

9. The structure as defined in claim 8 wherein said fulcrum means comprises a raised bead on one of said garment supporting members and a mating groove on the other garment supporting member.

10. The structure as defined in claim 1 wherein the fulcrum means comprises a pair of cooperating members, one on each of said garment-supporting members.

11. The structure as defined in claim 6 wherein the end portions of said wire are normally parallel prior to assembly with said garment-supporting members, wherein the end portions merge into upstanding portions, and wherein the wire is under tension when assembled with said garment-supporting members, the ends of said end portions exerting opposing inward forces upon a wall of each slot, and the upstanding portions exerting outward, opposing forces upon a wall of each slot.

12. The structure of claim 7 wherein cooperating tongue and groove members are provided on said extensions.

13. The structure as defined in claim 11 wherein the upstanding portions converge toward the upper portions thereof, and wherein said upstanding portions converge into angularly inclined portions which converge into said hook portion.

14. The structure as defined in claim 9 wherein the end portions of said wire are normally parallel prior to assembly with said garment-supporting members, wherein the end portions merge into upstanding portions, and wherein the wire is under tension when assembled with said garment-supporting members, the ends of said end portions exerting opposing inward forces upon a wall of each slot, and the upstanding portions exerting outward, opposing forces upon a wall of each slot.

15. The structure as defined in claim 14 wherein the upstanding portions converge toward the upper portions thereof, and wherein said upstanding portions converge into angularly inclined portions which converge into said hook portion.
